UNITED STATES PATENT OFFICE.

WILLIAM O. LOTT, OF COLUMBUS, OHIO.

BRAKE SHOE.

Application filed September 12, 1921. Serial No. 499,944.

To all whom it may concern:

Be it known that WILLIAM O. LOTT, a citizen of the United States, residing at Columbus, in the county of Franklin and

5 State of Ohio, has invented certain new and useful Improvements in Brake Shoes, of which the following is a specification.

This invention relates particularly to improvements in the construction of brake-shoes, particularly those of the type designed for use upon railway rolling stock, an object of the invention being to produce a brake-shoe wherein renewable and replaceable wheel engaging sections are provided, 10 which, when worn, are capable of being individually replaced in order that there will be a minimum amount of wastage when the wearing surfaces of said sections are worn away to such an extent as to require replacement.

Ordinarily, it is a common practice in the construction of brake-shoes with wheel engaging sections of integral arcuate formation, preferably formed from cast iron and reinforced by means of a steel backing. These sections are of one piece construction throughout the height of a brake-shoe, and consequently when worn or in any way damaged, so as to be rendered unfit for service, the same must be replaced in their entirety. By this construction considerable wastage is present in the form of scrap, and the present invention aims particularly to provide a brake-shoe wherein the wheel engaging portions thereof include a plurality of similar interchangeable sections, which are connected with the body of the shoe in such manner that the sections may be either collectively or selectively replaced upon the 25 body of the shoe so that breakage and wear thereof may be overcome by the employment of one or more of such sections, instead of requiring the replacement of the entire wheel engaging surfaces of a brake-shoe, as is now customary.

A further object of the invention resides in a construction whereby the replaceable wheel engaging sections of the brake-shoe may be quickly and positively connected with the body of the brake-shoe and to this end the head or body of the brake-shoe has detachably connected therewith by means of a wedge pin construction, a retaining strip with which is connected a plurality of replaceable wheel engaging sections, the said sections having their inner faces provided

with substantially dovetail grooves which are adapted to be removably placed upon the retaining strip, removable members provided at the ends of said strips for retaining the wear blocks or sections against accidental displacement thereon, the construction being such that when the blocks or sections are carried by the strips and the latter directly secured to the head of the brake-shoe by the wedge pin construction, the entire assembly will be rigidly united in a manner free from relative movement and capable of being employed with the same efficiency as the standard one piece construction now in common usage.

For a further understanding of the invention, reference is to be had to the following description and to the accompanying drawings, in which:

Figure 1 is a view in side elevation of the improved brake-shoe construction employed in carrying out the present invention.

Figure 2 is a vertical sectional view taken through the shoe in its entirety.

Figure 3 is a horizontal sectional view taken on the line 3—3 of Figure 1.

Figure 4 is a detail perspective view of one of the wearing blocks or sections.

Figure 5 is a perspective view of the retaining strip, and,

Figure 6 is a similar view of the brake head.

Referring more particularly to the details of the invention, use is made of a brake-shoe 1 which is formed to include a head or body 2 of standard construction and with which is associated a removable and replaceable wheel engaging assembly 3, which comprises the present invention. The body or head 2 is formed to include the usual rearwardly extending spaced flanges 4, which are suitably apertured as at 5 for pivotal association with the usual brake beam construction for a freight or passenger car. The forward face 6 of the head 2 is generally of arcuate formation, but is provided with recesses 7 in which are located forwardly projecting lugs 8, through which registering slots 9 extend, the said lugs being relatively spaced, as usual, to provide an intervening socket 10, the outer faces of the lugs 8 being generally of arcuate formation and are located to register with the outer arc of the head. The recesses 7 space the lugs 8 from the curved outer extremities 11 of the head, which are formed to include

transversely extending webs 12 having openings 13 formed therein for arcuate registration with the slots 9. It will be observed that the slots 9 and the openings 13 vary in width, in order that the same will be adapted to receive the usual standard curvilinear wedge pin 14, employed in uniting the assembly 3 with the body 2.

The assembly 3 includes a base in the nature of a metallic retaining strip 15. This strip is adapted to conform with the arcuate formation of the outer part of the body 2 and is preferably formed from steel plate material, the ends thereof being inwardly or rearwardly turned as at 16 to produce shoulders. These strips are adapted to receive a plurality of cast iron wearing blocks or sections 17, which are of duplicate formation and may be employed at any position on the outer face of the retaining strip. These blocks are secured to the retaining strip by having their rear faces provided with substantially dovetail grooves 18, which receive the strip 15, the said strip in cross section corresponding to the formation of the grooves 18, which is accomplished by beveling the outer edges of the strip as indicated by the numeral 19. It will be observed that the strip 15 is of substantially the same width throughout its length, and this construction admits of the placing of the block 17 thereon by inserting the blocks upon the strip from the ends of the latter. The operative positions of the blocks upon the strip may then be maintained by the provision of L shaped angle members 20, which have their shorter legs 21 inserted through openings 22 provided in the ends of the strip 15 in order that the legs 21 will engage with the end blocks 17 so as to prevent displacement on the part of said blocks. The longer legs 23 of the angle members are situated on the rear faces of the strip 15 and extend parallel therewith. Accidental removal of the angle members is preventable by inserting cotters 24 through openings provided in the shoulder projections 16.

The strip 15 and the block 17 positioned thereon are now capable of being directly secured to the arcuate forward face 6 of the body 2. This may be accomplished by providing the strip 15 with an inwardly directed stirrup 25, which is adapted to be positioned within the socket 10 of the body, and to be confined between the adjoining faces of the lugs 8. The stirrup is formed with registering openings 26 which are adapted to align with the slots 9 provided in the lugs 8. By this construction, it will be apparent that when the wedge pin 14 is driven into place, the same will pass through the openings 13 formed in the extremities of said body, the slots 9 provided in the lugs 8 and the openings 26 formed in the stirrup 25. By reason of the wedge shaped forma-

tion of the said pin, its connection in the manner described with the body 2 will result in drawing the assembly 3 toward the face 6 of the body with sufficient frictional pressure to produce a very rigid assembled construction, wherein weakness or relative movement in and between the parts of the shoe will be eliminated. If one or more of the blocks should become worn or broken, the damaged member can be readily replaced by removing the assembly 3 from the body 2. This permits the intact blocks to remain within the assembly and the damaged member conveniently removed, repaired or substituted. Thus, breakage or wear may be locally overcome, a feature which eliminates to a very great extent wastage now commonly prevalent in brake-shoe construction. Again, it will be observed that the blocks are of identical formation and therefore may be situated at any desired position within the assembly. It will also be understood that by slight changes in the lay of the block 17, the latter may be adapted to the driving wheels of a locomotive, or that other equivalent devices may be employed in lieu of the members 20 for retaining the blocks in their applied positions to prevent creeping thereof on the strip 15. In view of these conditions, it is intended that such changes may be made in the construction of the shoe without departing from the spirit of the invention as defined by the following claims.

What is claimed is:

1. In a brake-shoe, a body, a retaining strip conforming to the contour of the outer part of said body, means serving to removably connect said strip with said body, a plurality of selectively removable wear blocks carried by said body, and removable means carried by the ends of said strip and overlapping the ends of said blocks for retaining said blocks in a relatively fixed position of operation upon said strip.
2. In a brake-shoe, a body provided with an arcuate outer face having a socket formed intermediately thereof, a retaining strip shaped to conform with the outer face of said body, and having openings in its ends, wear blocks of duplicate formation removably carried by said strip, a projection formed intermediately of the length of said strip and arranged to be positioned within said socket, a wedge pin of tapering formation arranged to pass through aligned openings formed in said body and projection for drawing said strip and blocks toward and retaining the same in engagement with the outer face of said body and angle members removably associated with said openings for retaining the blocks in fixed position on said strip.
3. In a brake-shoe, a body formed to include an arcuate outer face having a socket

formed intermediately thereof, an arcuate metallic strip conforming and positioned adjacent to the outer face of said body, removable wear blocks of duplicate formation 5 positioned upon said strip, shoulders provided at the ends of said strip, members in engagement with said shoulders for retaining said blocks against circumferential placement upon said strip, a projection 10 formed with said strip intermediately of its length and arranged to be positioned within said socket, and an arcuate tapering wedge pin arranged to pass through registering openings formed in said body and projection for frictionally uniting the said blocks 15 with said body.

In testimony whereof I affix my signature.

WILLIAM O. LOTT.
